UNITED STATES PATENT OFFICE.

ARTHUR E. HAUCK, OF NEW YORK, N. Y.

PROPELLER ATTACHMENT FOR BOATS.

No. 818,245.

Specification of Letters Patent.

Patented April 17, 1906.

Application filed August 5, 1905. Serial No. 272,938.

To all whom it may concern:

Be it known that I, ARTHUR E. HAUCK, a citizen of the United States, residing at New York, in the county of New York and State 5 of New York, have made certain new and useful Improvements in Propeller Attachments for Boats, of which the following is a specification.

My invention is an improvement in that 10 class of propellers which are adapted to be detachably connected with boats and suspended in the water at the stern.

My invention includes novel and improved 15 features, as hereinafter set forth and claimed, the same being illustrated in the accompanying drawings, in which—

Figure 1 is a longitudinal section of my improved apparatus or propeller attachment arranged in the position for use, the outline 20 of the stern of a boat being shown by dotted lines. Fig. 2 is a side view, in reduced proportions, showing the same apparatus in the folded position as when detached from the boat. Fig. 3 is a view illustrating details of 25 construction by which the two hinged portions of the apparatus are rigidly secured to each other when the propeller is in working position. Fig. 4 is a plan view of the apparatus or attachment in working position. 30 Fig. 5 is a transverse section on the line 5 of Fig. 4. Fig. 6 is a perspective view of one of the adjustable bars by which the horizontal portion or platform of the apparatus is secured upon the deck and stern of a boat. 35 Fig. 7 is a perspective view, including the rear portion of the platform, adapted to be secured upon the stern of a boat, together with the driving-shaft and its bearing. Fig. 8 is a perspective view of the rigid bracket or 40 frame in which the propelling mechanism proper is arranged and supported. Fig. 9 is an enlarged horizontal section on the line 9 of Fig. 1. Fig. 10 is a vertical section of the 45 rear steering-wheel, parts for locking the same and the propeller in any desired position being illustrated in side view.

As shown in Figs. 1, 2, and 4, A indicates a 50 rectangular metal platform or frame adapted to be placed and supported upon the rear or stern portion of a boat, and B a frame carrying the propelling mechanism proper and having a hinged connection with said platform A, but provided with means for securing it in vertical position, as in Figs. 1 and 4 and as required for propulsion.

I will now proceed to describe the details

of construction, arrangement, and operation of the parts A and B, together with those attached thereto. The platform A rests horizontally upon the stern-deck of a boat or 60 upon the framework thereof and is secured in place mainly by means of two bars 1, (see Figs. 4, 5, 6,) which are arranged transversely beneath the platform A in suitable guides or keepers 2, in which they may be clamped by 65 means of screws 3. The outer ends of the bars 1 are curved to form what may be termed "goosenecks" 4 and provided with clamp-screws 5. In practice these bars are drawn out and the goosenecks 4 applied to 70 the gunwales or side edges of the boat or to other fixed portions of the latter and clamped by the screws 5. Screws 3 being then also tightened, the platform will be secured rigidly in the required position with its sides 75 equidistant from the sides of the boat.

The part B, in which the propelling mechanism is supported and has its bearings, comprises the following parts, which have a hinged connection with the platform A at a, 80 Fig. 1, by means of a broad bracket or arm 6: The propeller 7 is mounted upon a horizontal shaft 8, having a bevel-gear 9, which meshes with a corresponding one, 9^a, keyed upon a vertical shaft 10, which is driven 85 from the horizontal shaft 11, having its bearings in a box 12, secured upon the platform A. The base of the bearing 12 (see Fig. 7) may be solidly constructed and the upper portion thereof constructed as a cap 12^a, the 90 driving-shaft 11 having a series of collars 11^a, running in suitable grooves in the respective parts 12 12^a. An oil-box 13 is provided in the upper portion of the bearing and communicates with the shaft and collars by suitable ducts, as shown. Power for driving the shaft 11 is communicated thereto by any suitable means or motor, the same being arranged on the platform A or otherwise, as conditions and judgment may dictate. The 95 driven shaft 10 has its upper bearing in a tube 13, which is fixed in the four-armed bracket or frame. (Illustrated in Fig. 8.) Such bracket and the tube 13, before referred to, constitute the main portions of the hinged 100 part B. The tube 13 is held in the upper ring 14 of the bracket, and the curved arm 15 of the latter is provided at its lower end with a smaller ring 16, which is alined with the upper one, 14. The lower ring 16 constitutes a 105 bearing for a hollow rotary shaft 17, the upper end of the same projecting into the lower 110.

portion of the fixed tube 13 and provided with antifriction-bearings, as will now be described. Thus the rotatable tube 17 is provided with a horizontal flange 18, which is enclosed in a circular box and arranged between antifriction-balls, as shown in Fig. 1. The said box is formed by enlarging the lower end of the tube 13 and providing it with a pendent internally-threaded flange 10 into which the vertical flange of a short tube 19 is screwed, as shown. By this arrangement an antifriction-support is obviously provided for the rotary shaft 17. An antifriction-bearing, whereby it is held in vertical position, is further provided by means of rollers 20, (see Fig. 9,) having their bearings in the sides of the fixed tube 13 and the removable short tube 19. In other words, the rollers 20 work in contact with the side of the shaft 17, being held rotatably in recesses provided in the parts 13 and 19. The shaft 17 is connected with a horizontal bearing 21, which constitutes a bearing for the propeller-shaft 8. The latter is provided with a collar 21', abutting a sleeve 22, whose inner threaded end is screwed into the adjacent internally-threaded tubular portion of the bearing 21. By this means the gear 9 of the propeller-shaft 8 is held duly engaged with the gear 9^a of the driving-shaft 10. It is obvious that this means provides for taking up wear at any time, so that the gears are held duly in mesh. To further provide for a nice adjustment of the propeller-shaft, I arrange a set-screw 23 in the inner solid portion of the bearing 21, the same abutting the inner end of the said shaft. The outer bearing of the shaft is provided by a collar 24 and a cap 25, which is threaded internally to adapt it to be screwed on the tubular nut 22 and also incloses the said collar 24. By this means I provide for such adjustment of the bearing as may be required from time to time. Beneath the propeller 7 I arrange a guard-plate 26, whose inner end is provided with a screw-stem 27, by which it is secured in the lower pendent tubular portion of the bearing 21.

It is apparent that by applying power to the driving-shaft 11 the vertical shaft 10 will be driven correspondingly and the propeller 7 thereby rotated with like speed, provided the meshing gears be of like size as in this case. Assuming that the bearing 21 be adjusted in line with the axis of the boat, the propulsive effect will obviously be applied in the same direction; but by means of the rotatable shaft 17 and the bearings therefor before described the propeller may be shifted around the axis 10 at any required angle for guiding the boat in different directions, so that when desired the function of a rudder is performed by the propeller in addition to its ordinary function. For adjusting such shaft 17, and thereby placing the propeller at different angles, as may be required, I employ

the following means: A vertical shaft 28 is arranged in bearings 29 (see Fig. 8) of the curved portion or yoke 15 of frame B and provided at the top with a steering-wheel 30 and near its lower end with a gear 31, that meshes with a corresponding gear 32, keyed upon the hollow shaft 17 and arranged above the lower ring 16 of the frame B. It is apparent that by rotating the shaft 28 through the medium of the steering-wheel 30 the shaft 17 may be rotated while the propeller 7 is at rest or in motion for setting the propeller at any angle to the axis of the boat as may be required for steering the latter in any direction. A foot-platform 33 (see Figs. 1 and 4) is provided for the steersman, the same being rigidly attached to and supported by the tube 13. In other words, said foot-platform 33 forms a rigid attachment of the hinged portion B of the apparatus. In connection with the steering-wheel and the shaft 28 I provide means for locking them in any required position, so that the propeller 7 may be set at any required position and then locked in said position. As a rule, the lock 90 will be applied for holding the propeller with its shaft in line with the axis of the boat, in which case supplemental steering mechanism will be utilized. The locking means are as follows: A ratchet-collar 34 is secured upon a fixed support of the platform 33, and a lever 35 is pivoted to an arm pendent from the steering-wheel 30. A spiral spring 36 presses the inner end of said lever into engagement with the ratchet 34, and a push-bar having a head 37 is attached to the other end of the lever, so that by depressing it the steering-wheel and shaft 28 are unlocked.

I provide a supplemental and manually-operated steering mechanism, the same consisting of a rudder 38, (see Fig. 1,) having a vertical shaft 39, which is pivotally attached at 40 to the yoke 15 of frame B and provided at its upper end with a cross-bar 41, from which cords or wires 42 extend forward through guides 43 on the platform A to the shaft 44 of a hand steering-wheel 45, the said shaft having its bearing in a suitable bracket 46, forming an attachment of the front end of the platform. It is apparent that by rotating the wheel 45 a boat may be steered by means of the rudder 38 without recourse to the propeller-adjusting mechanism before described, and, on the other hand, if the rudder be left free the boat may be steered by means of the propeller, as described.

As shown in Fig. 8, right-angular arms 15^a diverge from the upper ring 14 of frame B, their vertical members being provided with holes for receiving screws, the said holes 125 when the frame B is in vertical and working position, as shown in Figs. 1, 3, coinciding with holes in vertical lugs 47, forming rigid portions or attachments of the rear end of the platform A. Clamp-screws 48, passing 130

through the coincident openings of the parts 15^a and 47, serve to secure the frame B and its attachments in the vertical working position. (Indicated in Figs. 1 and 4.) By removing such fastenings 48 the whole hinged portion of the apparatus may be swung on the hinge *a* in the position beneath the platform and practically parallel thereto. In other words, the part B and all its attachments 5 may be folded together with the platform A when detached from a boat, so that the same will occupy a minimum space, as required for transportation or storage. For securing the parts in the folded position a strap 49 10 may be passed under the hollow shaft 17 and through slots provided in lugs 50, that are 15 pendent from the side edges and front portion of the platform A. When the part B and its attachments are thus folded, the 20 transverse bars 1, by which the platform is secured to the boat, are drawn out of the keepers 2 and inserted in keepers 2^a, (see Fig. 1,) so that they are held longitudinally parallel to the platform instead of being 25 transverse thereto. This position is indicated by full lines, Fig. 2.

Having thus described my invention, what is claimed, and desired to be secured by Letters Patent, is—

30 1. The improved propelling attachment for boats, comprising a platform or frame, means for securing it to the stern of a boat, a driving-shaft arranged on said platform, and a frame hinged to the first-named one and 35 adapted to be folded therewith, means for securing the foldable frame in working position, and a propeller and propelling mechanism connected with the foldable frame and 40 adapted to be operatively connected with the aforesaid driving-shaft substantially as described.

45 2. The improved boat-propelling attachment comprising a platform and means for securing it to the stern of a boat, a frame hinged thereto and provided with means for 50 securing it rigidly in working position, a propelling mechanism including a propeller proper and means for driving it, the propeller being adapted to be set at different angles to 55 the axis of a boat, and means for adjusting it 50 in such position, substantially as described.

55 3. A boat-propelling attachment comprising a platform and a frame hinged thereto, and propelling mechanism carried thereby, 60 and means for securing the platform to a boat, the same comprising bars which are 65 slidable transversely in keepers and provided with means for securing them to the sides of the boat and clamping them in the 70 keepers, substantially as described.

75 4. In a boat-propelling attachment, the combination with a frame adapted for support upon the stern of a boat, and a frame hinged thereto and provided with a propeller and means for driving the same, of adjust-

able bars arranged transversely on the platform and having goosenecks adapted to engage the sides of the boat and means for clamping them in place, substantially as described.

70 5. The combination, with a frame adapted to be supported upon and secured to the stern of a boat, of a frame secured to the first-named frame, a vertical driving-shaft arranged in said frame, a hollow rotatable 75 shaft through which the same passes, a propeller having a shaft provided with bearings forming a fixed attachment of said hollow shaft, an antifriction-bearing and support for the hollow shaft, and means for rotating it 80 for adjusting the propeller in different positions, substantially as described.

6. The combination, with a rigid frame, of a propeller attachment comprising a hollow shaft having a horizontal bearing and provided at its upper end with a horizontal flange supported in said rigid frame, a propeller having a shaft arranged at right angles to said hollow shaft, a driving-shaft operatively connected with the propeller-shaft and 90 arranged within the hollow shaft, and means for rotating the latter, substantially as described.

7. The combination, with a rigid frame having a tubular pendent portion, a hollow 95 rotatable shaft projecting upward in the lower portion of such fixed tubular portion, antifriction-rollers arranged between the two parts, and means for supporting the hollow shaft vertically, a propeller and a propeller-shaft arranged in suitable bearings forming a horizontal attachment of the hollow shaft, and a driving-shaft passing through the latter and operatively connected with the propeller-shaft, substantially as described.

100 8. The combination, with a frame having a tubular portion arranged vertically therein, the lower portion of the latter being enlarged radially and provided with a pendent flange which is screw-threaded interiorly, a hollow rotatable shaft projecting into such tubular portion and provided with a horizontal flange, a short tube applied to the tubular shaft and having an upwardly-projecting and exteriorly-threaded flange adapted to screw 115 into the flange of the fixed tubular portion, and antifriction-balls applied between the respective parts to furnish both vertical and horizontal bearings, a driving-shaft passing through such tubular portion and the hollow shaft, a horizontal bearing applied to the lower end of the hollow shaft, and a propeller and propeller-shaft, the latter being connected with the driving-shaft, and means for rotating the hollow shaft for setting the propeller in different positions, substantially as 120 described.

125 9. The combination with a frame, a rotatable shaft having its bearings therein, and provided at its lower end with a horizontal 130

bearing, a propeller and a propeller-shaft arranged in such bearing, the driving-shaft operatively connected with the propeller-shaft, a rotatable steering - shaft operatively connected with the aforesaid hollow shaft, and a steering-wheel applied thereto, substantially as described.

10. The combination, with the tubular part 13 and the hollow shaft 17 having its 10 bearings in the latter, a propeller and a propeller-shaft, and a driving-shaft therein also having bearings in the hollow shaft, a steering-shaft 28 having bearings in the fixed frame, meshing gears applied to the hollow 15 shaft and steering-shaft, and a steering-wheel applied to the steering-shaft, substantially as described.

11. The combination, with a rigid frame, and propelling mechanism including a hollow 20 rotatable shaft having its bearings in and supported by such frame, and provided at its lower end with a horizontal bearing, a propeller-shaft arranged in the latter, a steering-shaft which is operatively connected with 25 such hollow shaft for adjusting the propeller at different angles, a steering-wheel applied to such steering-shaft, means for locking the steering-wheel and thereby holding the propeller fixed in any position to which it may be 30 adjusted, and a manually-operated steering mechanism comprising a rubber hinged upon the rear portion of the aforesaid frame, and wires and a steering-wheel for adjusting the same, substantially as described.

35. 12. The combination, with a rigid frame and steering mechanism including a hollow rotatable shaft, a propeller-shaft having its bearings in an attachment of the lower portion of said shaft, a steering-shaft operatively 40 connected with the hollow shaft, a steering-wheel applied to such steering - shaft, a notched collar surrounding the shaft and fixed on the frame, and a spring-catch adapted to be manually released, the same normally 45 engaging the said collar and forming an attachment of the steering-wheel, where-

by the propeller may be locked in any required position, substantially as described.

13. The combination, with the hollow shaft, a vertical driving-shaft arranged therein, a horizontal bearing applied to the lower end of the hollow shaft, a propeller having a shaft arranged in said bearing, meshing gears applied to the respective shafts, a collar applied to the propeller-shaft, and a nut screwed into the hollow bearing and abutting said collar and thus serving to hold the gears in mesh, substantially as described.

14. The combination, with the hollow shaft, a driving-shaft arranged therein, a horizontal bearing applied to the lower end of the hollow shaft, a propeller-shaft arranged in such bearing and gears operatively connecting it with the said driving-shaft, a fixed collar and an adjustable nut bearing against 65 the same, and a set-screw applied to the inner end of the propeller-shaft for adjusting the same as required, substantially as described.

15. The combination, with the hollow 70 shaft, and a driving-shaft arranged therein, of the horizontal bearing applied to the lower end of said hollow shaft, a propeller-shaft arranged in said bearing, a sleeve-nut screwed into one end of the bearing, a cap screwing 75 upon the outer end of the nut, and a bearing for the shaft inclosed between the nut and cap, substantially as described.

16. The combination, with a frame adapted to be secured upon the stern of a boat, of 80 a frame and propelling mechanism carried thereby, said frame being hinged to the first-named one and adapted to be folded beneath the same substantially parallel thereto, and means connected with the first-named frame 85 for securing the hinged frame in the folded position, substantially as described.
